United States Patent Office

Des. 215,493
Patented Sept. 30, 1969

215,493

EXHAUST ANALYZER OR SIMILAR APPARATUS

Michael D. Burridge, Los Altos, Calif., assignor to Sylvania Electric Products Inc., a corporation of Delaware

Filed Nov. 18, 1968, Ser. No. 14,521

Term of patent 14 years

Int. Cl. D10—11

U.S. Cl. D52—6

FIG-1

FIG-2

FIG-3

FIG-4

FIGURE 1 is a perspective view of an exhaust analyzer or similar apparatus showing my new design;

FIGURE 2 is a front view thereof;

FIGURE 3 is a side view thereof; and

FIGURE 4 is a top view thereof.

The undisclosed side of the apparatus is a mirror image of the side shown, and the rear is solid and plain in appearance.

I claim:

The ornamental design for an exhaust analyzer or similar apparatus, as shown and described.
